Primary Examiner — Samantha Q Lawrence*Assistant Examiner* — Thanh Luu Wong(74) Attorney, Agent, or Firm — Sterne, Kessler, Goldstein & Fox P.L.L.C.(57) CLAIM

The ornamental design for a surprise egg, as shown and described.

DESCRIPTION

FIG. 1 is a top, front perspective view of a surprise egg showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a front perspective view thereof in an opened state; and,

FIG. 9 is a front perspective view thereof in an opened state. The circular object shown in broken line in FIGS. 8 and 9 represents a decorative item that can be applied to the surface of the egg, and the broken lines in the figures form no part of the claimed design.

1 Claim, 6 Drawing Sheets(56)
